UNITED STATES PATENT OFFICE.

WEAR L. DRAKE, OF CHICAGO, ILLINOIS.

HOLLOW BRICK AND TILE MOLDING MACHINE.

SPECIFICATION forming part of Letters Patent No. 239,230, dated March 22, 1881.

Application filed September 4, 1879.

To all whom it may concern:

Be it known that I, WEAR L. DRAKE, of the city of Chicago, in the county of Cook and State of Illinois, have invented a new and useful Improvement in Hollow Brick and Tile Molding Machines, of which the following is a full, clear, concise, and exact description, reference being had to the accompanying drawings, forming a part thereof, and in which—

10 Figure 1 represents a longitudinal elevation with the front cut away; Fig. 2, an end elevation, showing the roller-rack M; Fig. 3, the horizontal die-plate i and adjustable core-pin j, pivoted as shown at r, to its support-frame K, a section thereof being shown in connection with attachment-box L, Fig. 1; Figs. 4 and 5, different styles of die-plates; Figs. 6 and 7, respectively, sectional and superficial views of an adjustable core-pin consisting of any number of parts, as p p p; Fig. 8, an end elevation, in which is shown another style of core-pin, J" J", the separate parts being connected by wires x x. Dividing-wire v" is also shown.

15 B B' are the covers of clay-boxes C C', which are symmetrical.

20 The shaft G is journaled as shown at K K', and is provided with driving-pulleys a b c. a and c run free on the axle G, one carrying a straight and the other a crossed belt, which are applied alternately to the rigid pulley b.

25 F is the pinion, geared with the wheel E, which is provided with a thread and revolves or turns upon the piston or screw D, driving it longitudinally back and forth with the plungers W W', which are attached to either end of D.

30 Heretofore the piston D, or "plunger shaft," as it is sometimes called, has been driven back and forth by means of bevel-gear wheels, requiring to accomplish such motion five bevel-wheels and two shafts with spur and pinion wheels, which combination of mechanism I dis-claim.

35 f f' are knee-joints. g is the connecting-rod. e e' are levers attached thereto, as shown. When the levers are thrown up, as shown, the pinion is raised, and thereby thrown out of gear with wheel E, and the machine stops. The pinion is thrown into gear by moving the 40 levers either to the right or left. In large machines this work is done mechanically.

Clay properly tempered is thrown alternately into the boxes C C', and, by means of the plungers W W', forced out through the die-plates h h', and thereby formed into brick, tile, or 45 moldings, which are received upon a roller-rack, M, placed at either end of the machine, and by means of a cutter, N, provided with wires, as shown, divided into pieces of such length as required. 50

Prior to my invention the core-pin and die-plate were cast in a single piece. I find that the two may be made separate, as shown in Fig. 3, and when so constructed the core-pin becomes adjustable, and the size and shape of 55 the hollow or opening in the brick, tile, or moldings may be varied simply by changing the core-pin. Whatever may be the style of core-pin, whether consisting of one or more parts, its holder, which may be about one inch 60 wide and twenty-two (22) inches long in a large machine, is beveled on the inner side and left flat or with a plane upper surface, so that the clay is made to lap-weld after it passes the holder and before it passes the core-pin, 65 and thus the brick or tile are prevented from cracking. 70

The attachment-box L may be used in molding large tile, which are run down through a die-plate placed horizontally, as shown. Tile 75 may, however, be handled with much greater facility when run out horizontally upon roller-racks. The difficulty heretofore experienced in doing this, when the tile are large, is that when fresh molded they are liable to collapse 80 or fall in when placed upon their sides; but by the use of my core-pin J" J", Fig. 8, a portion of the clay is left within the opening and serves to support the sides of the tile until they are partially dried. This portion is then 85 left loose and is readily removed. The wires x x divide or separate this support or core as it passes through the die from the sides of the tile, yet leaving it in place, so that it serves to support the tile until they are sufficiently 90 hardened to support their own weight, as before described. 95

The parts J" J" may be increased in number and connected by wires, as x x, substantially as shown, and thereby two or more supports may be left within the opening. During 100 this process of molding large tile the dividing-

wire v'' is not used. It is designed for dividing a large tile and making thereof two smaller ones, when placed as shown in Fig. 8, and in this latter case the wires $x x$ are removed and the tile comes from the machine with two openings, the portion between the parts $J'' J''$ of the core-pin being left solid; but on coming against the wire v'' the tile is divided into two parts, either one of which is in itself a complete tile.

By increasing the number of parts $J'' J''$ of the core-pin and using the necessary number of dividing-wires v'' the number of tile or moldings that may be run out together may be indefinitely increased.

I claim—

1. The piston D, provided with a thread and plungers W W', in combination with the pulleys a , b , and c , shaft G, and pinion F, whereby power is applied to the wheel E, which turns upon the thread, driving the piston D longitudinally back and forth, substantially as and for the purpose specified.

2. The knee-joints ff , attached to the frame K K and side A, in combination with the connecting-rod g and levers ee , arranged substantially as shown and described.

WEAR L. DRAKE.
